UNITED STATES PATENT OFFICE.

JOHN DUFF, OF PHILADELPHIA, PENNSYLVANIA.

OIL-CONTAINER.

1,149,506.

Specification of Letters Patent.

Patented Aug. 10, 1915.

Application filed August 10, 1914. Serial No. 856,059.

To all whom it may concern:

Be it known that I, JOHN DUFF, a citizen of the United States, residing at Philadelphia, in the county of Philadelphia and 5 State of Pennsylvania, have invented certain new and useful Improvements in Oil-Containers, of which the following is a specification, reference being had to the accompanying drawings.

- 10 This invention comprehends certain new and useful improvements in oil containers or what are commonly called "oil cans" for use in applying a liquid lubricant to shaft bearings or other parts of machinery, and 15 the invention has for its primary object a simple, durable and efficient construction of device of this character, the parts of which are so arranged that the spout is hingedly connected to the body of the can, whereby it 20 may be easily swung to one side, to an inoperative position, when it is necessary to fill the can or clean the same out, and as readily swung back to its operative position where it is held by a sprung latch, this 25 construction and arrangement of parts providing that the filling opening of the can body, can be very readily and quickly exposed without the necessity of unscrewing the spout, as is commonly the case, the spout 30 being permanently connected to the body, and all liability of its becoming lost thereby being precluded, while at the same time the necessity of laying the spout down to fill the can, so that it is liable to roll into some 35 of the machinery, or become clogged up, is obviated. And the invention also aims to generally improve devices of this character, so as to render them more useful and commercially desirable.
- 40 With these and other objects in view, as will more fully appear as the description proceeds, the invention consists in certain constructions, arrangements and combinations of the parts that I shall hereinafter 45 fully describe and claim.

For a full understanding of the invention, reference is to be had to the following description and accompanying drawing, in which,

50 Figure 1 is a side elevation of the device, the spout being shown swung to one side in dotted lines, and Fig. 2 is a fragmentary elevation with the spout open.

Corresponding and like parts are referred 55 to in the following description and designa-

nated in all of the views of the accompanying drawing by like reference characters.

Referring to the drawing, the numeral 1 designates the body of the oil can and 2 the spout thereof. In the present embodiment 60 of the invention, the lower or base end of the spout is secured within a collar 3, which is provided with an annular flange 4 to afford an increased bearing surface. The lower face of the collar 3 is provided with 65 a depending marginal flange coacting with the lower end portion of the spout 2 to afford a recess or socket, in which a packing or gasket 5 of soft rubber or other suitable material or substance is seated, whereby 70 when the spout is in its operative position, this gasket will fit firmly down upon the annular flange 6 which defines the opening at the top or apex of the body 1, thereby 75 obviating all liability of leakage.

The collar 3 is formed with an offset extension 7 transversely apertured and adapted to fit in between the apertured pintle ears 8 formed in any desired way upon the can body at the top thereof, a pintle 9 being inserted through said ears and extension 7, whereby the spout is hingedly connected to the body and may be swung to one side to the position indicated by dotted lines in Fig. 1, or be swung upwardly to its relatively vertical and operative position with the gasket fitting firmly down upon the annular flange 6.

In order to securely hold the spout in its operative position, a spring latch 10 is provided. This is secured at one end to the can body 1 by rivets or in any other way, and extends upwardly along the side of the can body toward the flange 6, the relatively upper end of the latch being provided with 90 a hook 11, the extremity of which is beveled, as indicated at 12. To co-act with the latch, the collar 3 is formed at a point diametrically opposite the pintle extension 7 with a tapered extension 13, the upper and 95 lower faces of which are beveled, as indicated at 14 and 15, respectively, whereby the relatively free or hooked end of the latch 10 does not have to be grasped and retracted in the operation of opening or closing the 100 can body, but it is only necessary to grasp the spout with one hand and the body of the can with the other hand and swing the spout to one side to its vertical position, the beveled formation of the tapered extension 110

13 and of the extremity of the hook 11, permitting the tapered extension 13 of the collar 3 to readily move into and out of engagement with the hook while at the same 5 time, after the hook has once engaged the upper bevel 14 of the collar, the spout will be securely held in its operative position and all accidental movement thereof will be prevented. It is to be noted that in the normal 10 relation of the parts, with the spout in its operative position, the inner face of the hook 11 is held spaced from the adjoining edge of the tapered extension 13, so that when the parts wear, such wear will be compensated for.

While the accompanying drawing illustrates what I believe to be the preferred embodiment of my invention, it is to be understood that the invention is not limited 20 thereto, but that various changes may be made in the construction, proportions and arrangements of the parts without departing from the scope of the invention as defined in the appended claim.

25 What is claimed, is:

As a new article of manufacture, an oil container comprising a body provided with

a filling opening, an annular upstanding flange defining said opening, an upstanding ear carried directly by the body at one side 30 of the flange, an upstanding resilient latch member carried directly by the body at one side of the annular flange and diametrically opposed to the ear, a spout provided adjacent its lower end with a collar adapted to 35 overlie the annular flange of the body, said collar being provided with diametrically opposed extensions, one of said extensions being pivotally engaged with the ear, the opposite extremity being adapted to coact with 40 the latch member for maintaining the spout in operative position, said collar being provided with a marginal flange coacting with the lower end of the spout to afford an annular recess, and a gasket within said recess 45 engageable with the flange defining the filling opening when the spout is adjusted to operative position.

In testimony whereof I hereunto affix my signature in the presence of two witnesses.

JOHN DUFF.
